PROPARGYLAMINE AS AN ANTI-DEPRESSANT
 Edward F. Elslager, Ann Arbor, Mich., assignor to Parke,
 Davis & Company, Detroit, Mich., a corporation of
 Michigan
 No Drawing. Filed Oct. 9, 1963, Ser. No. 314,861
 1 Claim. (Cl. 167—65)

The present invention relates to pharmaceutical compositions useful in the treatment of depression and cardiovascular ailments such as hypertension and to methods for treatment embodying the use of these compositions.

More particularly, the present invention relates to pharmaceutical compositions containing as an active ingredient propargylamine in free base or physiologically acceptable inorganic and organic acid addition salt form. As examples of some of the many physiologically acceptable salts contemplated, there may be mentioned the hydrochloride, hydrobromide, hydroiodide, nitrate, bisulfite, bisulfate, hemisulfate, perchlorate, acetate, palmitate, stearate, hemipamoate, picrate, decanesulfonate, 4-chloro-2 - (5-chlorosalicyl) - phenoxide, hydroxynaphthoate, dodecylsulfate, cyclohexanesulfamate, phenolphthalein, trichlorophenoxyde, 2,2' - thiobis(4,6-dichlorophenoxyde), deoxycholate, 7-chloro - 4-hydroxy-3-quinolincarboxylate, dihydroxyisonicotinate, bromonaphthoxide, hemiadipate p - toluene - sulfonate, hemi - (5,5'-thiodisalicylate), 3,5-dichlorosalicylate, taurocholate, dioctylsulfosuccinate and 2,6-di-iodo - 4 - nitrophenoxide. The acid addition salts are conveniently formed from the free base by mixing the free base with at least an equivalent amount of the acid in a solvent in which the salt is insoluble, particularly after chilling, thereby permitting recovery of the desired salt as a solid phase. Whereas both the free base and salt forms are useful for the purposes of the invention, the salts are generally preferred in those cases where increased stability and water solubility are desirable. In general, the choice of anion is not critical since the above-mentioned cation constitutes the active moiety. The selection and provision of salts for the purposes of the invention will be understood by those skilled in the art in accordance with methods and considerations which will be known to them. Preferred compositions of the invention are those which include as an active ingredient propargylamine hydrochloride. The invention also contemplates compositions which include not only propargylamine in free base or acid addition salt form but also a therapeutically effective amount of a diuretic agent such as hydrochlorothiazide, chlorothiazide, hydroflumethiazide, benzhydroflumethiazide and the like.

The invention is based on the unexpected finding that propargylamine and its acid addition salts at well tolerated dosage cause a striking elevation in tissue norepinephrine levels and also possess significant anti-reserpine activity. For example, propargylamine hydrochloride administered to rats at a dose of 40 mg./kg. daily for four days by the intraperitoneal route elevates the norepinephrine level beyond control levels by as much as 130% in the heart and 185% in the brain, in accordance with the assay procedure described in *Acta Phys. Scand.*, vol. 118, Sup. 33, page 45 (1955).

According to the present invention, pharmaceutical compositions are produced by formulating the free base propargylamine or physiologically acceptable acid addition salts thereof in dosage unit form. Such compositions are constituted with pharmaceutical carriers or diluents. In view of the oral activity of propargylamine and its salts, dosage unit forms for oral administration are particularly suitable, such as tablets, powders, capsules, solutions and suspensions in which the propargyl-

amine compound is incorporated with a carrier or diluent. Solid carriers and diluents include sugars such as lactose and sucrose; cellulose derivatives such as sodium carboxymethyl cellulose, ethyl cellulose, methyl cellulose and cellulose acetate phthalate; gelatin (including hard and soft shell capsules); talc, corn starch, stearic acid and magnesium stearate. Liquid carriers and diluents suitable for use include vegetable oils such as peanut oil, cottonseed oil, sesame oil, olive oil, corn oil and oil of theobroma; polyethylene glycol; propylene glycol; glycerine; sorbitol, ethanol; and water. Suitable preservatives and flavoring agents can also be incorporated in such compositions. In the production of dosage forms such as tablets, an enteric coating or sugar coating can be applied to make the medicament more palatable. If administration by the parenteral route is desired, the composition can be formulated in ampoule form as a suspension or solution in a liquid diluent. Other therapeutic agents can also be incorporated with the compositions.

The concentration of the propargylamine compound (reckoned as free base content) in the compositions can be varied within wide limits but, for practical purposes, is preferably at least 5% by weight. As will be appreciated, the upper concentration limit is not critical.

It will be understood that the dosage regimen for the compositions of the invention will vary, depending on various factors. In general, however, the daily oral dosage range, calculated as propargylamine free base content, is about 10 to 250 mg. per kilogram of body weight, in single or divided doses; and the dosage is continued until the condition under treatment is relieved.

In the preparation of dosage unit forms such as tablets or capsules, the quantity of medicament furnished by each dosage unit form is selected such that the proper dose can be reached by administering either one or a reasonable number of the dosage units. For convenience of manufacture and ease of administration, it is preferable that such dosage forms contain at least 2.5 mg. or more up to 125 mg. of the propargylamine compound (calculated as free base) per unit.

The invention is illustrated by the following examples showing various suitable dosage forms and the preparation thereof.

EXAMPLE 1

A solution of salicyclic acid (1.38 parts by weight) in ether (15 parts by volume) is added with stirring to a solution of propargylamine (0.55 part by weight) in ether (10 parts by volume). The resulting crystalline product, propargylamine salicylate, is collected by filtration, washed with ether and recrystallized from dioxane-ether; M.P. 140-146° C. The corresponding propargylamine hydrochloride is obtained by treating the ethereal propargylamine solution with excess hydrogen chloride and isolating the resulting crystalline hydrochloride salt, in the same manner, M.P. after recrystallization from methanol-ether 178-181° C.

Likewise, other propargylamine salts, as follows, are obtained by mixing an ether or acetone solution of one equivalent of the respective acid (one-half equivalent for dibasic acids) with the propargylamine solution and isolating the resulting crystalline salt product:

Propargylamine sulfate; M.P. 162-166° C., from methanol-ether.
 Propargylamine 2,2' - thiobis - (4,6-dichlorophenoxyde); M.P. 171-177° C., from 2-propanol.
 Propargylamine acetate; M.P. 86-92° C.
 Propargylamine 3-hydroxy-2-naphthoate; M.P. 150-159° C., from 2-propanol.
 Propargylamine p-toluenesulfonate; M.P. 156-158° C., from acetone.

3

EXAMPLE 2

Formula for emulsion (100 ml.)

Propargylamine	mg	100
Isopropyl palmitate	ml	20
Polyethylene sorbitan 60 (Tween 60)	g	3
Sorbitan 80 (Span 80)	g	2
Sugar, U.S.P.	g	10
Sodium benzoate	g	0.5
Flavors, q.s.		
Color, q.s.		
Distilled water, q.s. ad. 100 ml.		

MANUFACTURING INSTRUCTIONS

Dissolve the propargylamine in the isopropyl palmitate by heating. Add the Span 80 and Tween, heating to 65° C., so that all are melted together. Dissolve the sugar and sodium benzoate in water and heat to 67-70° C. Add the water phase to the oil phase with thorough agitation. Allow the emulsion to cool and then add the flavor and color, mixing well. Homogenize the emulsion.

EXAMPLE 3

Formula for solution (100 ml.)

Propargylamine hydrochloride	mg	200
Sugar, medium granular cane	g	20
Sodium citrate, U.S.P.	g	0.25
Sodium benzoate, U.S.P.	g	0.5
Citric acid, anhydrous, U.S.P.	g	0.4
Glycerin, U.S.P.	ml	5
Raspberry imitation flavor	ml	0.5
F.D. & C. Red No. 4	mg	0.003
Distilled water, q.s. ad. 100 ml.		

MANUFACTURING INSTRUCTIONS

- (1) Dissolve the propargylamine hydrochloride in 60 ml. of water with stirring. Add the sodium benzoate, sodium citrate, citric acid, sugar, glycerin, dye and flavor.
- (2) Adjust the volume to 100 ml. with distilled water. Filter the solution.

EXAMPLE 4

Formula for hard shell capsules

Propargylamine hydrochloride	G.	2.5
Milk sugar powder, U.S.P.	175	
No. 4 opaque capsule, gelatin hard shell		

MANUFACTURING INSTRUCTIONS

- (1) Pass the propargylamine hydrochloride and milk sugar through a No. 30 mesh screen. Blend thoroughly in a twin shell blender.
- (2) Fill the powder blend into No. 4 opaque hard shell gelatin capsules using a capsule filling machine. Yield, approximately 1000 capsules each containing 2.5 mg. of propargylamine hydrochloride. Instead of propargylamine hydrochloride in the above formulation, one can use an equal amount of other acid addition salts or propargylamine. For example, one can use any of the salts set forth in Example 1.

EXAMPLE 5

Formula for 5 mg. tablets

Propargylamine hydrochloride	G.	5
Sugar with 3% starch, powdered	165	
Milk sugar, U.S.P., powder	165	
Solution "A" (acacia solution), q.s.		
Corn starch, sifted	30	
Talc, sifted	10	
Magnesium stearate, U.S.P.	3	

MANUFACTURING INSTRUCTIONS

- (1) Blend the propargylamine hydrochloride, powdered sugar, and milk sugar in a twin shell blender.

4

- (2) Wet granulate the powder blend with solution "A." Finish granulating with distilled water, if necessary.
- (3) Screen the wet granulation through a No. 6 stainless steel screen.
- (4) Dry overnight at 120-130° F.
- (5) Reduce the dried granulation through a No. 14 stainless steel screen.
- (6) Blend in the corn starch, talc and magnesium stearate.
- (7) Compress the blend on a rotary tableting machine using $1\frac{3}{4}2$ " concave punches. Yield, approximately 1000 tablets each containing 5 mg. of propargylamine hydrochloride.

Other salts of propargylamine such as those of Example 1 can be substituted for the hydrochloride in this formulation. An alternative materials list for making 1000-lot capsules by this procedure, each containing 50 mg. of propargylamine p-toluenesulfonate is the following:

20	Propargylamine p-toluenesulfonate	G.	50
	Dibasic calcium phosphate	140	
	Milk sugar, U.S.P., powder	140	
	10% w/w. polyvinylpyrrolidone solution, q.s.		
25	Corn starch, sifted	40	
	Talc, sifted	10	
	Magnesium stearate, U.S.P.	3	

EXAMPLE 6

Formula for solution (100 ml.)

30	Propargylamine sulfate	mg	200
	Sugar, medium granular cane	g	20
	Sodium citrate, U.S.P.	g	0.25
	Sodium benzoate, U.S.P.	g	0.5
35	Sulfuric acid, q.s. to pH 5.0		
	Glycerin, U.S.P.	ml	5
	F.D. & C. Red No. 4	mg	0.003
	Cherry flavor	ml	0.5
40	Distilled water, q.s. ad. 100 ml.		

MANUFACTURING INSTRUCTIONS

- (1) Dissolve the propargylamine sulfate in 60 ml. of water with stirring. Add the sodium benzoate, sodium citrate, sugar, glycerin, dye and flavor.
- (2) Adjust the pH to 5.0 with sulfuric acid solution.
- (3) Bring the volume up to 100 ml. with distilled water. Filter the product.

EXAMPLE 7

Formula for suspension (100 ml.)

50	Propargylamine 3-hydroxy-2-naphthoate	G.	1.0
	Polyethylene sorbitan 60 (Tween 60)	0.1	
	Sodium saccharin	0.02	
55	Cyclamate sodium (sodium Sucaryl)	0.03	
	Sugar, med. granular	10	
	Methylcellulose (Methocel, U.S.P.)	0.2	
	Flavor, q.s.		
60	Sodium benzoate	0.5	
	Sodium citrate	0.25	
	Distilled water, q.s. ad. 100 ml.		

MANUFACTURING INSTRUCTIONS

- (1) Dissolve the polyethylene sorbitan 60 in water; hydrate the methylcellulose.
- (2) Wet the propargylamine 3-hydroxy-2-naphthoate with the polyethylene sorbitan solution and add to the hydrated methylcellulose solution.
- (3) Add the sodium saccharin, sodium sucaryl, sugar, sodium benzoate, sodium citrate, dye and flavor.
- (4) Bring up to volume with distilled water and homogenize the suspension. Each 5 ml. aliquot of the resulting suspension contains 50 mg. of propargylamine 3-hydroxy-2-naphthoate.

An alternative formulation containing a different, and also less readily water-soluble, salt of propargylamine is the following:

Propargylamine salt with one formula weight of 2,2'-thiobis-(4,6-dichlorophenol)	mg	200	5
Tween 80 (Polysorbate 80)	g	0.5	
Purified montmorillonite clay (Veegum, high viscosity)	g	0.6	
Sodium carboxymethylcellulose	g	0.5	
Sodium benzoate, U.S.P., powder	g	0.5	10
Sugar, medium granular cane	g	10	
Citric acid, anhydrous	g	0.1	
Sorbitan 20 (Span 20)	g	0.40	
F.D. & C. Yellow No. 5	mg	3.5	15
Flavor, q.s.			
Distilled water, q.s. to 100 ml.			

MANUFACTURING INSTRUCTIONS

- (1) Hydrate the clay; add the sodium benzoate.
- (2) Dissolve the polysorbate in water, wet the propargylamine salt with the solution, and the resulting mixture with 1.
- (3) Mix the sugar and sodium carboxymethylcellulose. Add slowly to 2. Mix until dissolved.
- (4) Add the citric acid and sorbitan.
- (5) Add the dye and flavor, and adjust the volume

up to 100 cc. with distilled water. Homogenize the suspension. Each 5 ml. aliquot of the resulting suspension contains 10 mg. of propargylamine salt.

I claim:

A method of combatting depression which comprises administering to a depressed animal a composition in dosage unit form containing as active ingredient an amine compound of the group consisting of propargylamine and physiologically acceptable acid addition salts thereof, the dosage being sufficient to provide about 10 to 250 mg. of the amine compound calculated as free base per kilogram of body weight per day.
